UNITED STATES PATENT OFFICE

158,876

HOUSEHOLD UTILITY WAGON

Laurel Lowell, Weston, Mass.

Application September 23, 1948, Serial No. 148,725

Term of patent 14 years

(Cl. D14—3(4))

To all whom it may concern:

Be it known that I, Laurel Lowell, a citizen of the United States of America, and a resident of Weston, in the county of Middlesex, Commonwealth of Massachusetts, have invented a new, original, and ornamental Design for a Household Utility Wagon, of which the following is a specification, reference being had to the accompanying drawing, forming part thereof.

Fig. 1 is a perspective view of a household utility wagon, showing my design.

Fig. 2 is another perspective view, taken from the left of Fig. 1.

I claim:

The ornamental design for a household utility wagon, substantially as shown.

LAUREL LOWELL.
